UNITED STATES PATENT OFFICE.

ETHEL GORDON THOMPSON, OF MINNEAPOLIS, MINNESOTA.

DOLL FIGURE.

1,392,981.

Specification of Letters Patent. Patented Oct. 11, 1921.

Application filed July 24, 1920. Serial No. 398,747.

To all whom it may concern:

Be it known that I, ETHEL GORDON THOMPSON, a citizen of the United States, residing at Minneapolis, in the county of 5 Hennepin and State of Minnesota, have invented certain new and useful Improvements in Doll Figures, of which the following is a specification.

My invention relates to doll figures and 10 an object is to provide figures which are formed of suitable sheet material and which are so constructed that they may be joined together in succession and readily detached when desired. Another object is to provide 15 figures of this character which will be attractive both to children and grown people, and which can be used either singly or in assembled condition.

The full objects and advantages of my invention will appear in connection with the 20 detailed description thereof and the novel features embodied in my inventive idea will be particularly pointed out in the claims.

In the accompanying drawings,—

25 Figure 1 is a front view of one of my doll figures. Fig. 2 is a rear view of the doll figure shown in Fig. 1. Fig. 3 is a front view of another doll figure. Fig. 4 is a rear view of the doll figure shown in Fig. 3. 30 Fig. 5 is a front view of two of the doll figures which illustrate the manner in which a number of them may be formed into a ring of doll figures by attaching their hands together. Fig. 6 is a plan view showing a plurality of doll figures secured together in 35 ring-like manner. Fig. 7 is a detail view in horizontal section with the two hand members joined together.

Referring to the drawings, the numeral 10 40 in Fig. 1 designates the front of a doll figure and the numeral 12 in Fig. 2 designates the rear thereof, this figure having right and left-hand members provided respectively with pairs of slots 14, 16 and 18, 20. The 45 numeral 22 in Fig. 3 designates the front of another doll figure and the numeral 24 in Fig. 4 designates the rear thereof, this figure having right and left-members, the ends of which at 26 and 28, respectively, are so 50 shaped as to be capable of sliding snugly through the pair of slots 14, 16, or through the pair of slots 18, 20. Figs. 5 and 7 show how the doll figures may be fastened together in this manner. Any desired number 55 of the doll figures may be fastened to-

gether one after the other, and by joining the two figures at the ends a ring of doll figures may be formed, as indicated in Fig. 6, in which the numerals 30, 32, 34, 36, 38, 40, 42 and 44 designate positions where the 60 hands are joined. The appearance of the various figures may be varied according to the taste or wish of the artist and the hand members are located at the same height, so that any desired number of figures may be 65 joined together in succession to form a ring of figures standing in upright position. The figures are preferably formed by painting or printing in suitable colors on sheet material such as cardboard of sufficient 70 stiffness so that they will stand erect when the hand members are joined together. A convenient method is to paint or print the figures in colors on sheets of cardboard, a front and a rear view of each figure being 75 produced as illustrated in Figs. 1 and 2 and in Figs. 3 and 4, these figures being then cut out. Considering Figs. 1 and 2 for instance, the two portions designated 10 and 12 are 80 complementary, and by pasting their reverse sides together a complete figure will be produced. The same is true of the figures designated 22 and 24 in Figs. 3 and 4, and the same principle may be employed for various 85 figures.

The manner of using my invention and the advantages thereof will be readily understood from the foregoing description. The doll figures may be used at children's parties, or other parties, and when assembled 90 in ring-like form will stand on the table and may, if desired, be placed around a birthday cake or other object. The figures may be readily taken apart and one given to each person as a souvenir. They may also 95 be used as favors and place cards. They may be assembled in ring-like form and placed on the rotating table of a phonograph, when they will appear to be dancing, and by arranging the figures so that they 100 face inwardly and outwardly in succession they will appear to be performing a grand right-and-left. While I have shown doll figures of children and such figures constitute a desirable embodiment of my invention, 105 I do not wish to be limited to the use of doll figures of children or persons.

I claim:

1. A series of doll figures formed of sheet material, and hand members on said figures 110

located at the same height, some of said hand members being provided with slots and others being provided with extensions adapted to be engaged in said slots whereby said figures may be secured together in succession and readily detached when desired.

5 2. A series of doll figures, integrally con-

nected limb members extending from said figures, and integrally formed coöperating elements on said limb members to detachably secure the figures in succession.

10 In testimony whereof I hereunto affix my signature.

ETHEL GORDON THOMPSON.
